UNITED STATES PATENT OFFICE.

CLARA B. PATTERSON, OF PHILADELPHIA, PENNSYLVANIA.

SKIRT-SUPPORTER.

937,852.

Specification of Letters Patent. Patented Oct. 26, 1909.

Application filed April 27, 1907. Serial No. 370,550.

To all whom it may concern:

Be it known that I, CLARA B. PATTERSON, of Philadelphia, in the county of Philadelphia and State of Pennsylvania, have invented certain new and useful Improvements 5 in Skirt-Supporters, whereof the following is a specification, reference being had to the accompanying drawings.

My invention relates to an improvement 10 in skirt supporters, and its object is to provide a supporter which may be attached to the garments of the wearer without the use of thread, and which is invisible after the 15 skirt has been attached to the waist of the wearer.

In its present embodiment it comprises a 20 loop or eye formed integrally with a pin and safety catch or guard, which pin is adapted to be passed through the waist band, and lower edge of the waist, said loop depending 25 from said pin when secured in position on the wearer. Upon the upper edge of the skirt a hook is secured, said hook being also integrally formed with a pin point and guard. This portion of the supporter when 30 in its final position on the skirt of the wearer has its hook depending and adapted to register with the loop or eye on the waist.

In the accompanying drawings Figure I, 35 is an elevation of that part of the supporter which is intended to be fastened to a waist. Fig. II, is a plan view of the same. Fig. III, is an elevation of that part of the supporter, which is intended to be fastened to a skirt. Fig. IV, is a plan view of the same. Fig. V, is a view showing the application of 40 a pair of eye pins of the supporter secured in position upon a waist, and also securing a skirt-supporter band in place. Fig. VI, is a view showing the application of a pair of 45 hook pins of the supporter secured in position upon the inside of the top of a skirt, said skirt top being shown turned downwardly. Fig. VII, is a central sectional view through the hook and loop members, in engaged position as the skirt and waist 50 would appear on the wearer.

In said figures,—the eye pin 1, is formed 55 of a single piece of wire bent at substantially its central portion into a semi-circular loop 2. One end of said wire is bent at substantially right angles to form the portion 3, at the left hand side of said loop as shown in Fig. I, said wire being then bent to form 60 the spring coil 4, and then continued in a straight line to form the pin bar 5, having

a point 6, bent as shown in Fig. I. The other end of said wire is bent at substantially right angles to form the portion 7, and then bent into the coils 8, and 9, to form a 65 guard for the pin point 6. The point 6, of the pin is curved as shown in Fig. II, to keep it from scratching the wearer.

The hook pin 10, is formed of a single 70 piece of wire bent at substantially the central portion of its length into a hook 11. This hook is formed of two substantially parallel portions 12, and 13, each of which is bent downwardly and back upon itself to form the parallel strands 15, and 16, respectively, said strands being again bent 75 backwardly upon themselves in the same plane forming parallel strands 17, and 18. The end of the wire extending from the strand 17, is bent at right angles thereto 80 into the length 19, and then into a spring coil 20, and afterward extended on an arc of a circle to form a pin 21, which is provided with a curved point 22. The arc of the pin 21, conforms substantially with the 85 contour of the waist of the wearer and the point 22, is bent in order that it may not project so as to scratch the wearer. By reference to Fig. III, it will be seen that that portion of the wire which forms the 90 hook and the adjoining bends crosses the pin bar, and the major portion of the hook 11, extends below the level of said pin bar 21, and the bends at the upper end of the hook which engage the loop 2, are just 95 about on a line with said pin bar. This construction throws the engaging portions of the hook and eye members well below the upper edge of the skirt when in position upon the wearer, whereby they are effectively hidden from view. The end of the 100 wire extending from the strand 18, is bent at right angles thereto forming the straight portion 23, which is afterward curved to form a pin guard 24. In Fig. V, a pair of 105 the loop members of the supporter are shown in position upon a waist 30, one on each side of the separating line 33. In attaching these members a ribbon 31, or waist band, is placed against the waist 30, and 110 secured thereto by means of the eye pins 1. Upon the inside of the skirt 32, the hook members are fastened as shown in Fig. VI, said members being spaced so as to register with the loop members upon the waist when the skirt is secured in position. In this figure the top of the skirt is shown turned

downwardly to show how the hooks are secured thereto. By reference to Fig. VII, it will be seen that the hooks 10, are inserted through the loops 2, of the eye pins 1, thereby securely holding the skirt to the waist.

It will be noted from the description above set forth that by pinning the waist band 31, directly to the waist by means of the eye pins, as shown, an arrangement is provided 10 which is greatly simplified over that heretofore in use. With previous constructions it has been customary to attach the waist band to the waist by means of a set of hooks and eyes sewed in position upon said waist band 15 and waist; and also attach the skirt to the waist band by means of a second set of hooks and eyes sewed in position upon said waist band and skirt. Or, the means employed have been exposed to view in an 20 objectionable manner.

Having thus described my invention, I claim:

A skirt supporter, including in combination, a supporting loop formed of a single 25 wire bend to form a loop, a securing pin and a retainer for said pin, a supporting hook formed of a single wire bent upon

itself to form parallel members adapted to enter the supporting loop, said members being bent upon themselves and spaced to 30 form a supporting base for the supporting loop, said members being then bent outwardly away from each other substantially in the plane of the supporting base, and then upon themselves, and extended to a 35 point beyond the base of the hook, one of said members being then bent outwardly and coiled, and extending across the base of the hook, to form a retaining pin, and the other member being bent outwardly in 40 the opposite direction, and curved to form a retainer for said pin, whereby said loop and said pin are adapted to be engaged by the band of the waist and the band of the skirt, and be substantially concealed between said 45 bands.

In testimony whereof, I have hereunto signed my name, at Philadelphia, Pennsylvania, this twenty-sixth day of April 1907.

CLARA B. PATTERSON.
